TROPHY

Harry A. Reising, La Grange, Ill.

Application August 2, 1954, Serial No. 31,710

Term of patent 7 years

(Cl. D29—28)

To all whom it may concern:

Be it known that I, Harry A. Reising, a citizen of the United States and a resident of the village of La Grange, county of Cook, State of Illinois, have invented a new, original, and ornamental Design for a Trophy, of which the following is a specification, reference being had to the accompanying drawing, forming a part thereof in which:

Fig. 1 is a perspective view of a trophy showing my new design;

Fig. 2 is a top plan view thereof;

Fig. 3 is a side elevational view thereof;

Fig. 4 is a front elevational view thereof; and

Fig. 5 is an elevational view of the side opposite that of Fig. 3.

I claim:

The ornamental design for a trophy, substantially as shown.
